(57) **CLAIM**

The ornamental design for a strap for a bag, as shown and described.

DESCRIPTION

FIG. 1 is a perspective view of a strap for a bag showing the new design. The strap is shown attached to an exemplary bag, such as a purse.

FIG. 2 is a front view thereof;

FIG. 3 is a back view thereof;

FIG. 4 is a side view thereof;

FIG. 5 is a side view thereof;

FIG. 6 is a top view thereof; and,

FIG. 7 is a bottom view thereof.

The broken lines in the drawings illustrate environment and form no part of the claimed design.
